E. BERNIER

TICKET HOLDER

Filed Jan. 24, 1924

UNITED STATES PATENT OFFICE.

ERNEST BERNIER, OF DETROIT, MICHIGAN, ASSIGNOR OF ONE-HALF TO JEAN B. CHARETTE, OF DETROIT, MICHIGAN.

TICKET HOLDER.

Application filed January 24, 1925. Serial No. 4,422.

To all whom it may concern:

Be it known that I, ERNEST BERNIER, a former subject of the King of England, and who have declared my intention of becoming a citizen of the United States, and who is residing in Detroit, in the county of Wayne and State of Michigan, have invented a new and useful Improvement in a Ticket Holder, of which the following is a specification.

My invention relates to a new and useful improvement in a ticket holder, adapted for containing tickets which are issued in large numbers and used separately, such as single-ride tickets for use on street cars and the like.

An object of the invention is to provide a ticket holder of this class, adapted for containing a number of tickets, and provided with a mechanism for feeding the tickets therefrom, at the will of the operator, singly.

Another object of the invention is the provision of a ticket holder having a casing provided with spring operated mechanism for retaining the tickets in a position adapted for engaging the removing members.

Another object of the invention is the provision of a ticket holder of this class, so constructed and arranged as to be easily filled with tickets.

Other objects will appear hereinafter.

The invention consists in the combination and arrangement of parts hereinafter described and claimed.

The invention will be best understood from a reference to the accompanying drawings, which form a part of this specification, and in which:

Fig. 1 is a perspective view of the invention, showing a ticket projected therefrom.

Fig. 2 is a longitudinal, central, vertical, sectional view of the invention.

Fig. 3 is a sectional view taken on substantially line 3—3 of Fig. 2.

Fig. 4 is a side elevational view of the feeding mechanism.

Fig. 5 is a bottom plan view of the feeding mechanism.

Fig. 6 is a section view taken on line 6—6 of Fig. 3.

The invention in its preferred form, comprises a box-like housing 9, having notches 10 and 10' formed in the side walls,

adjacent one end thereof. A cover 11 is provided, which has depending lugs 12 and 12', at opposite sides, pivotally connected to the feeding walls of the housing 9. The structure is such that the cover 11 may be raised into vertical position, relatively to the box 9, the end edge of the cover 11 projecting downwardly into the notches 10 and 10'. This arrangement permits the mounting of the cover 11 on the housing 9 within the marginal limits of the housing, so that no projections extending from the end walls of the housing are necessary. It will also be noted that the cover 11 is slightly shorter than the housing 9, so that an open space is present extending across the housing 9 adjacent the end from which the tickets 30 are projected. This permits an inspection of the contents of the housing without opening the cover 11 and without necessitating the projection of the tickets 30 from the housing. It also affords means of raising the ticket 30 so as to clear the end wall 31 of the housing 9, should the follower described herein fail for any reason to function properly. One end of the cover 11 is provided with a depending tongue 13, which is adapted to engage against one of the end walls, so as to retain the cover in closing position. Formed in the cover 11 is a slot 14, through which projects a stem 15 having a head 16 formed thereon, and angularly turned transversely to the slot 14. This stem and head are punched out of a feeding member 17, which is provided, at one end, with an angularly turned edge 18, having a comparatively sharp edge. Guide members 19 and 20 are formed adjacent the edges thereof, extending longitudinally thereof. As shown in the drawings, the guide members are triangularly shaped and taper to one end.

Mounted in the box portion 9 is a spring member formed from a single strip having upstanding ears 21 and 22 formed adjacent the end of a stem portion 23. Tongues 24 and 25 are punched out of the main body of the spring positioned in the box 9 and curved upwardly, as shown in Fig. 2. A tongue 26 is punched out of the opposite end of the spring, centrally thereof, and curved upwardly. A feeding plate 27 is provided, having one end tapered, as shown in Fig. 3. The opposite end is provided with a tongue 28, which engages between 105 110

the tongues 21 and 22. This member is also provided with tongues 29 and 29', which engage, at opposite sides of the tongues 21 and 22, the tongues 21 and 22 being angularly bent over the tongues 29 and 29', so as to retain the feeding plate in operative position. When the feeding plate is assembled in the box, it is pressed downwardly toward the bottom thereof, so as to permit the folding of the tongues 21 and 22 into position for retaining the plate in operative position in the box. In order to press this feeding plate downwardly, toward the bottom of the box, the spring 10 tongues 24, 25, and 26 are pressed downwardly toward the bottom of the box, so that the feeding plate, when the tongues 21 and 22 are angularly turned, is held in close engagement with the angularly 15 turned portions of the tongues 21 and 22, against the tension of the spring tongues already mentioned.

As shown in Fig. 2 and Fig. 3, the feeding plate 27 projects substantially to the 25 end of the box in which the notches 10' and 10 are formed, so that the feeding plate may be said to project across said notches.

As shown in Figs. 1 and 2, the head 16 30 is thrust through the slot 14 and then angularly turned on the stem 15, so as to prevent the removal of the plate 17 from the cover.

When the tickets 30 are placed in the 35 box, the feeding plate 27 is pressed downwardly, against the tension of the spring tongues. The cover is then closed and a 40 slideable movement of the plate 17 will serve to bring the angularly turned edge 18 into engagement with the end edge of one of the tickets 30. A movement toward the opposite end of the slot of the head 16 will then cause the ticket 30 to be projected from the box 9, the upper edge of

the end wall 31 being positioned slightly 45 below the under surface of the cover 11, when the cover is in closed position, so as to provide a narrow space or slit through which the ticket 30 may be projected. On account of the spring tension on the feeding plate 27, the tickets are always retained in close engagement with the plate 17 and a formation of the angularly turned portion 18 of a height substantially the same as the thickness of the ticket to be used in 50 55 the device, assures a delivery of a single ticket through the slit upon a movement of the head 16, as described.

While I have illustrated and described the preferred form of structure, I do not 60 wish to limit myself to the precise details set forth, but desire to avail myself of such variations and modifications as come within the scope of the appended claim.

Having thus described my invention, 65 what I claim as new and desire to secure by Letters Patent, is:

A ticket holder of the class described, comprising a compartment adapted for the reception of a plurality of tickets; side 70 walls on said compartment, the opposite side walls each having a slot formed therein; a cover swingably mounted on said side walls and adapted for engaging at its lower edge in said slots upon movement to open 75 position, said cover being slightly shorter than said compartment the space extending between said slots being open; a spring held follower mounted in said compartment and adapted for normally retaining tickets 80 placed therein in close engagement with said cover; and slideable means mounted on said cover for projecting said tickets from said compartment individually at the end bearing said slots. 85

In testimony whereof, I have signed the foregoing specification.

ERNEST BERNIER.
